UNITED STATES PATENT OFFICE.

EARL L. BRINGMAN, OF MARSHALLTOWN, IOWA.

SHIELD FOR LOCOMOTIVE SHAKER-LEVERS.

1,358,516.

Specification of Letters Patent.

Patented Nov. 9, 1920.

Application filed January 31, 1919. Serial No. 274,220.

To all whom it may concern:

Be it known that I, EARL L. BRINGMAN, a citizen of the United States, residing at Marshalltown, in the county of Marshall 5 and State of Iowa, have invented certain new and useful Improvements in Shields for Locomotive Shaker-Levers, of which the following is a specification.

The present invention has reference generally to improvements in shields and more particularly relates to a shield for locomotive shaker levers.

It is the primary aim and object of this invention to provide a device of the above mentioned character designed to be connected to the furnace and floor of a locomotive beneath the firedoor and positioned about the shaker mechanism for the grate in consequence causing a saving of fuel by preventing it from falling onto the shaker mechanism subsequently falling on the track bed.

It is an additional and equally important object of this invention to provide a device 25 of the above mentioned character designed to be arranged about the shaker mechanism and constructed to accommodate the levers or handles in such a manner as to permit of free operation of the latter when it is desired 30 to shake the grate and as a result prevent large pieces of coal from clogging and interfering with an easy operation of the shaker mechanism.

Among the other aims and objects of this 35 invention may be recited the provision of a device of the above mentioned character wherein the number of parts are comparatively few, the construction simple, the cost of production low and the efficiency high.

40 Other objects, as well as the nature, characteristic features and scope of this invention will be more readily apparent from the following description taken in connection with the accompanying drawings, and 45 pointed out in the claims, forming a part of this specification.

The invention is clearly illustrated in the accompanying drawings, in which:—

Figure 1 is a perspective view showing 50 the device applied about the shaker mechanism, and

Fig. 2 is a longitudinal sectional detail view on the line 2—2 of Fig. 1, the shaker mechanism being shown in elevation.

55 Fig. 3 is a fragmentary plan view of the shield detached.

Similar characters of reference are employed in all of the above described views, to indicate corresponding parts.

Referring now, more particularly, to the accompanying drawings, there is illustrated a portion of a locomotive cab including a platform or floor 1 and the furnace 2 provided with a firebox door 3 while connected to the furnace and operating through and beneath the floor is the shaker mechanism generally designated by the numeral 4 over and about which is fitted the improved shield generally designated 5 designed to prevent coal from falling on the shaker mechanism and passing therethrough into the track bed (not shown), the purpose of the shield being to save fuel and prevent coal from interfering with an easy operation of the shaker mechanism.

The shaker mechanism may be generally stated as comprising a mounting 6, connected to the furnace 2 for operably supporting therein a shaft 7 from which depend arms 8, there being only one shown in Fig. 2, of the drawing, and the lower end of this arm is in turn connected with a link 9 having connection with a series of rocking bars B of a fuel feeding grate A of any ordinary construction located within the furnace.

Each of the arms 8 has formed thereon a hand lever 10 which extends upwardly from said shaft 7 for manual manipulation. At one side of each lever 10 is a stationary post 11, which projects from the mounting 6, and has pivotally connected thereto a swinging catch 12 for latching the lever 10 to prevent accidental movement thereof.

The catches 12 are bifurcated at their free ends to straddle the levers 10 when swung to engage therewith, and the engagement of the catches 12 with the levers 10 prevent the moving of said levers. When each catch 12 is to be released from the lever 10 adjacent thereto the said catch 12 is swung upwardly and laterally on its pivot away from the lever 10, so that the same is free for manual manipulation to actuate the grate bars of the grate in the furnace.

The shield in the present instance may be 105 said to consist of a main cover plate 13 and spaced side plates 14. The main cover plate includes an inclined portion 15 provided with a series of vertical slots 16 designed to be arranged about the handle levers 10 and 110 also provided at the sides of the slots with substantially rectangular openings 17 de-

signed to be arranged about the posts. In this connection the catches 12 are disengaged from the posts to permit of the application of the inclined portion of the main plate thereabout and are subsequently connected to the posts so as to lie on top of the inclined portion. An upper portion 18 continues from the inclined portion 15 and is formed at its upper edge with a substantially vertically disposed furnace engaging flange 19 designed to be fastened thereto through the instrumentality of suitable fasteners 20. The lower portion 21 of the main plate continues from the inclined portion 15 and is vertically disposed with respect to the floor or platform 1 being formed with a horizontally extending floor engaging flange 22. Opposed flanges 23 project from the side edges of the main plate 13 and are engaged by the adjacent upper edges of the side plates 14 which are secured thereto as by suitable fastening devices 24. Floor engaging flanges extend horizontally from the lower edges of the side plates 14 as indicated at 25. To further facilitate the retention of the side plates, the same are provided with openings so as to be arranged about the projecting reduced portions of the shaft 7 and these reduced portions are engaged by suitable retaining devices such as a nut 26.

In using the device, it is believed to be apparent that inasmuch as it is disposed beneath the door 3 any coal which accidentally falls from the shovel when the furnace is being fired will, instead of falling on the shaker mechanism as is usually the case, strike the shield 5 and be directed toward the floor 1. In this manner coal will not become wasted by passing by the shaker mechanism and falling on the track bed and moreover will not clog the shaker mechanism thereby interfering with the operation thereof. It is also apparent that owing to the slots 16, when the catches 12 are disengaged from the levers, the levers may be reciprocated for the shaking of the grate. The openings 17 of course permit of the disposition of the catches exteriorly of the shield so that they may be used in the usual manner and removably associated with the handle levers to hold the levers and consequently the shaker mechanism, against accidental movement when it is not desired to use the same.

It is believed in view of the foregoing description that a further detailed description of the operation of the invention is entirely unnecessary. Likewise, it is believed

that the advantages of the invention will be readily apparent.

Still further embodiments of the invention than those herein especially defined may be resorted to as conditions or preference may dictate, as may be in keeping with the hereto appended claims.

Having thus fully described the invention, what is claimed as new and desired to be secured by Letters Patent, is:—

1. A shield of the character described including a main cover plate provided with vertical slots and openings positioned to the sides of the slots for respectively accommodating the shaking handle levers and lever catch supporting posts of a grate shaking mechanism, attaching flanges on the main plate, and side plates secured to the sides of the main plate.

2. A shield of the character described including a main cover plate provided with vertical slots and openings positioned to the sides of the slots for respectively accommodating the handle levers and lever catch supporting posts of a grate shaking mechanism, attaching flanges on the upper and lower edges of the main plate, other flanges projecting from the side edges of the main plate, and side plates fastened to the last mentioned flanges for co-operating with the cover plate in preventing coal et cetera from lodging in or passing by the shaking mechanism.

3. A shield for the shaking mechanism, of a locomotive including a main plate having an inclined body portion provided with a plurality of vertical slots and openings positioned to the sides of the slots for respectively accommodating the handle levers and the lever catch supporting posts of the shaking mechanism the upper portion of the plate being adapted to continue from the main portion toward the furnace of the locomotive, and formed with an attaching flange, and the lower portion adapted to continue from the inclined portion toward the floor of the cab of a locomotive and provided with an attaching flange, other flanges projecting from the opposite side edges of the main plate, said plates designed to close the space between the main plate, the furnace and the floor of the cab of the locomotive, and means for detachably fastening the side plates to the last mentioned flanges on the main plate.

In testimony whereof, I affix my signature hereto.

EARL L. BRINGMAN.
